FEEDING MECHANISM FOR SEWING MACHINES

Nicholaus Knaus, Newark, N. J., assignor to The
Singer Manufacturing Company, Elizabeth,
N. J., a corporation of New Jersey

Application June 20, 1935, Serial No. 27,512

1 Claim. (Cl. 112—209)

This invention relates to improvements in sewing machines, and more particularly to an adjusting mechanism for differential or gathering feeding mechanism embodying two feed-dogs 5 which are given differential movements relative to each other.

The several features of the present invention will be clearly understood from the following description and accompanying drawings in which:—

Figure 1 is a top plan view, partly in section, showing my improved feed-adjusting mechanism embodied therein.

Figure 2 is a sectional view taken substantially along the line 2-2 of Figure 1.

Figure 3 is a rear elevation of a portion of a sewing machine showing my improved adjusting

Figure 4 is a perspective view of the feed-adjusting mechanism.

Figure 5 is a disassembled perspective view of the feed-adjusting mechanism.

As illustrated in the drawings, my improved feed-adjusting mechanism is shown applied to an overseaming machine such as that disclosed in the patent to A. Grieb, No. 933,033, dated Aug. 31, 1909. In the embodiment shown, 1 is the bed of the machine having suitable bearings in which are journaled a main-shaft 2, and rearwardly extending bearing supports 3 formed with suitable bearing apertures to receive the feed-rock shaft 4.

Fixed upon the feed-rock-shaft 4 is the feed-rocker 5 having two spaced lateral arms 6 and 7, each arm having an apertured end which receives a pivot-pin 8. The feed-rocker 5 receives an oscillatory movement from the main-shaft by means of a pitman 9 having one of its ends embracing an adjustable eccentric 10 on the main-shaft 2, and its other end connected by a pivot-pin 11 to the depending arm 12 which has its split-hub 13 secured to the feed-rocker 5.

Disposed intermediate the arms 6 and 7 of the feed-rocker and carried by the pivot-pin 8 is the enlarged apertured end 14 of the auxiliary feed-bar 15 which carries on its forwardly projecting end 16 the auxiliary feed-dog 17. A main feed-bar 18 is slidably carried on the auxiliary feed-bar 15, the main feed-bar being provided with a rib 19 which enters the channel 20 in the auxiliary feed-bar and a longitudinal aperture 21 which receives the stud 22 carried by the auxiliary feed-bar. The above described connection permits the main feed-bar to be reciprocated on the auxiliary feed-bar and independently thereof.

but connected thereto, so as to be moved up and down therewith. The forward end of the main feed-bar carries a main feed-dog 23 which is located in rear of and substantially in alignment with the auxiliary feed-dog 17.

The auxiliary feed-bar 15 overhangs the usual feed-lift eccentric 24 on the main shaft and a short pitman 25 embracing the feed-lift eccentric is pivotally connected to the bar 15 by means of a pivot stud 26 carried by the pitman. 10 Through this connection with the main shaft, the feed-bars receive their rising and falling movement. The above described differential feeding mechanism is substantially the same as that forming the subject of my Patent No. 1,959,- 15 719, dated May 22, 1934, to which reference may be had for a more detailed description.

To vary the throw of the main feed-dog relative to the auxiliary feed-dog the main feed-bar 18 is connected by the link 27 to the bell-crank lever 28 which is pivotally secured to the rocker-arm 7 by the pivot-stud 29. The lever 28 is formed with a rearwardly projecting thumb-piece 30 and a locking lever 31 is pivotally secured to the member 28 by the pivot-stud 32. A spring 33 having one of its ends reacting against the end of the thumb-piece 30 and its other end reacting against the locking lever urges the locking lever in a counterclockwise direction, as viewed in Figure 2. A plate 34 is clamped between the 30 rocker-arm 7 and the lever 28 by the screw 29 and a portion of the plate is notched to receive the feed-rocker 5 to hold the plate against turning movement relative to the feed-rocker (Fig. 5).

The plate 34 is formed with teeth 35 with which the teeth 36 of the locking lever 31 cooperate to hold the bell-crank lever 28 in its various operative positions. From the above it will be obvious that by pressing the thumb-piece and the locking lever together, the teeth 36 of the locking lever are disengaged from the teeth 35 of the plate 34 and the bell-crank lever 28 may then be swung about its fulcrum to adjust the end of the lever 28, to which the connecting link 27 is secured, nearer to or farther from the pivotal axis of the feed-rocker, thereby decreasing or increasing the feeding movement transmitted to the auxiliary feed-bar.

To indicate the amount of feeding movement given to the main feed-bar, in any adjustment of the bell-crank lever 28, the latter element is formed with an upstanding segmental portion 37 having suitable indicia thereon which cooperate with a fixed indicator finger 38 carried by the retaining plate 34. 55

Having thus set forth the nature of the invention, what I claim herein is:—

- Feeding mechanism for sewing machines including, a pivoted feed-rocker formed with laterally extending arms, mechanism for vibrating said feed-rocker about its pivot, a feed-bar having one of its ends pivoted to said feed-rocker, a second feed-bar carried by said first mentioned feed-bar for horizontal sliding movement relative to said first mentioned feed-bar, mechanism for raising and lowering said feed-bars in unison,

a link having one of its ends pivoted to one end of said second mentioned feed-bar, a member pivotally carried by one of the arms of said feed-rocker and pivotally connected to the other end of said link, and means for moving said member about its pivotal connection on the rocker-arm to bring the pivotal connection between said member and said link closer to or further away from the pivotal axis of said feed-rocker.
